TYING MACHINE WITH TWINE ARM GUARD

Robert G. Brown, Glenwood, Md., assignor to B. H. Bunn
Company, Chicago, Ill., a corporation of Illinois

Filed Oct. 18, 1966, Ser. No. 4,315

Term of patent 14 years

(Cl. D55—1)

FIGURE 1 is a front elevation in perspective of the tying machine with twine arm guard; and

FIGURES 2 and 3 are respectively side and rear elevations of the tying machine of FIGURE 1.

I claim:

The ornamental design for a tying machine with twine arm guard, as shown.
